UNITED STATES PATENT OFFICE.

JUDSON SHOECRAFT, OF ESKRIDGE, KANSAS.

ABSOLUTE AND PERMISSIVE BLOCK-SIGNALING SYSTEM.

1,311,718.

Specification of Letters Patent.

Patented July 29, 1919.

Application filed August 16, 1917. Serial No. 186,557.

To all whom it may concern:

Be it known that I, JUDSON SHOECRAFT, a citizen of the United States, and a resident of Eskridge, in the county of Wabaunsee and State of Kansas, have invented a new and useful Improvement in Absolute and Permissive Block-Signaling Systems, of which the following is a specification.

My invention relates to improvements in block signaling systems for railways and has particular application to a single signal system for use on single track railways provided with sidings.

The main object of the present invention is to provide an improvement to that system shown in my prior Patent, No. 1,229,155 of June 5, 1917. In said prior patent an interlocking block signaling system for single track railways was disclosed, whereby a train in one block when leaving such block and entering the next block would cause a danger signal to be displayed and would lock the signal in danger position while traveling through the last named block, so that the engineer of the following train would be advised as to the condition of the block ahead. The improvement in the present invention lies particularly in the provision of stationary electrical contacts disposed along the track and arranged to be engaged by a slideable contact shoe carried by the engine, the electrification of said stationary contact serving to permit the engine to proceed, but the cutting off of the current from the stationary contact resulting in the stopping of the train through the mechanism carried thereby, the latter mechanism forming no part of the present invention.

A further object of my invention is to provide means for automatically causing the electrification of said stationary contact members when the track is clear but to cut off the current from said contact members when another train is in the danger zone.

A further object of my invention is to provide a visible signal at each end of the section, that is to say, near each of the sidings, for indicating the condition of the section to a train approaching the same.

Other objects and advantages will appear in the following specification and the novel features of the invention will be particularly pointed out in the appended claims.

My invention is illustrated in the accompanying drawings, forming part of this application, in which,

Figure 1 is a diagrammatic view of one end of a section,

Fig. 2 is a diagrammatic view of the other end of the section.

In the drawings, the main track rails are shown at 1 and 2 respectively, this track being divided up into sections with a siding near the ends of each section, these sidings being shown at 3 and 4 respectively. Each section is divided up into a series of blocks such as those shown at A, B and C, these blocks being separated from one another by suitable insulation 5 arranged between the lines of rails at the meeting ends of the blocks to insulate the rails of one block from those of the adjoining blocks.

Located at the ends of each section, that is to say, adjacent to the sidings, are semaphores 6. These semaphores are shown diagrammatically. Each embodies a signal blade normally held in a clear position and adapted to move by gravity to danger position, and a motor m connected to the signal blade from suitable mechanism and adapted when energized to hold the signal blade at clear and to release the signal blade when de-energized so that the blade may move to a position to indicate danger.

Located at the meeting ends of the blocks are interlocking relays of a type which was fully set forth in the prior patent aforesaid and which are therefore shown in the present application diagrammatically. These relays are shown at 7^a, 7^b, 7^c and 7^d at the ends of the respective blocks A, B, C, D, and 8^a, 8^b, 8^c and 8^d at the adjacent ends of the respective blocks B, C, D and E. Each of these relays is provided with three sets of movable contacts, certain of these contacts being closed when the relays are energized and others being open when the relays are energized, and adapted to be closed when the relays are deenergized, as will be explained later.

Bridging the track rails 1 and 2 in each of the blocks is a battery such as those shown at K^a, K^b, K^c, K^d, K^e. At the ends of the adjoining blocks are the batteries 9, 10, 11 and 12, while at the block ends in the interior of the section, that is to say, those block ends which do not have a signal 6, are provided with auxiliary batteries such as those shown at 10^x and 11^x. At one end of the section is a battery P which operates a relay p at the opposite end of the section. A battery S at one end of the section operates

a relay s at the other end, as will be pointed out later.

- On each side of the track near the ends of each of the blocks are ramps or stationary contacts which are designed to be electrified, these contacts being engaged by shoes, not shown, on the engine for actuating electrical devices. Any suitable mechanism may be used, the purpose being to provide means
- 10 which will engage the contact and which will permit the train to pass when the contact is electrified, but which will automatically stop the train when current is cut off from the contact. The apparatus carried
- 15 by the train which works in conjunction with the electrified ramp or contact shoe forms no part of the present invention, this invention being limited to the means by which current is supplied to the contact shoe
- 20 automatically, or cut off automatically, depending upon the position of trains on the track.

In the drawings the ramps on one side of the tracks are shown at R^b , R^c , R^d , R^e and 25 on the other side at $R^{a'}$, $R^{b'}$, $R^{c'}$, and $R^{d'}$. It will be observed that the upper contacts of the relays 8^b , 8^c , 8^d and 8^e and 7^a , 7^b , 7^c and 7^d are prolonged so that when a set of 30 relays at the adjoining of two blocks, for instance, the relays 7^b and 8^e are deenergized, these upper movable contacts will fall down in such position that one locks the other by overlapping it and holding it down regardless of the subsequent energization of its 35 magnet. Moreover the locking feature applies to the other two movable contacts of each of the relays. This was fully set forth in the prior Patent, No. 1,229,155, mentioned.

40 From the foregoing description of the various parts of the system, the operation thereof may be readily understood.

Let us assume that a train T is in the block A and is approaching the block B 45 while there is a train T' in the block C approaching the block B. Consider first the condition when train T' first enters the section, that is to say, past the siding 4. Normally the batteries K^a , K^b , K^c , K^d , etc., energize the relays 7^a , 7^b , 7^c , etc., and 8^b , 8^c , 8^d , etc., respectively, so that these relays are holding up their contacts. As stated before, the battery P energizes the relay p at the opposite end of the section. This is done 50 over the following path: the conductor 15, contacts 16 and 17 of relay 8^e , conductor 18, contacts 19 and 20 of relay 8^d , conductor 21, contacts 22 and 23 of relay 8^c , conductor 24, relay p , wire 25 and by the return wire 55 26 back to the battery. Similarly the control of the relay s by the battery S may be traced through the contacts of the series of relays 7^a , 7^b and 7^d .

Now when the train T' first enters the 60 section it short circuits the first relay 8^e

which is normally held up by battery K^e . The contacts of this relay drop down and the energizing circuit of the relay p at the opposite end of the section, that is to say, between the blocks A and B, is broken at the contacts 16, 17 of the relay 8^e , thus deenergizing the relay p . The movable contact 27 of the relay p drops down and breaks the circuit which electrifies the ramp R^e , this ramp being connected normally to the battery 9 by 75 means of the conductor 28, contacts 27 and 29, contacts 30 and 31 and conductor 32. A train in the block A whose shoe meets the ramp $R^{a'}$ will therefore be stopped since it cannot get current to proceed. Obviously 80 this same thing will happen whether the other train be in the block C, D or E, that is to say, the ramp $R^{a'}$ will have the current cut off from it. If there is no train in the block A then the semaphore 6 will be at 85 clear, getting its energizing current over the following circuit: from battery 9 through 28, 34, contacts 35, 36, wire 37, through the motor M and by wire 38 to the battery 9. If, however, there is a train such as that shown 90 at T in block A approaching, then the relay 7^a will be deenergized or short circuited, its contacts will fall downward and the energizing circuit of the signal will be broken at the contacts 36, 35, thus permitting the 95 semaphore to fall down into the danger position. If a train T should disregard the signal and try to enter the block B, then the absence of current in the ramp R^e would prevent the train from entering by the mechanism carried thereon, not shown, and which 100 does not form any part of the present invention.

Obviously when the trains proceed out of the section then the batteries K^a , K^b , K^c , etc., are no longer short circuited and hence energize the relays 7^a , 7^b , 7^c , 8^a , 8^b , 8^c , etc., thus restoring the parts to their normal position. I have shown the effect of the entrance of the train T' into the section, but the entrance of 110 train T into the section has precisely the same effect on the ramps R^c , R^d , R^e , etc., at the opposite end of the section, for it will be observed that when the train T enters the block A the relay 7^a is deenergized. The 115 contacts of this relay as well as the relays 7^b and 7^c form part of the circuit of the relay s so that the breaking of the circuit of any of these relays will deenergize the relay s . The ramp R^e derives its current from the 120 battery 12 through the contacts 40 and 41 and through the conductor 42 so that current is taken off from the ramp, thus stopping any other train which attempts to get into the section.

When the train T' has proceeded into the block C the relays 8^c and 7^c are deenergized. This will, of course, take the current from the ramp $R^{a'}$ at one end of the section and R^d in the block D behind the train so as to 125

protect the train from a rear end collision. The fact that the relay p gets its current through the contacts of the relays 8^e and 8^a which are deenergized by the train T' when in the block C assures the dropping of the semaphore signal 6 to danger in block A when the trains T and T' are in the position shown in the drawing.

The visual signal in the block E in the rear of the train T' will show clear because there is no train in the block E . The ramp in the block E is deenergized by the dropping of the armature of the relay s . The signal still gets current from the battery 12 through the lowermost contact of the relay 8^e .

While the train stopping mechanism on the train forms no part of the present invention at the same time the object of electri- 20 fying or cutting off the current from the various ramps may be better understood when it is borne in mind that the ramp acts as a circuit breaker for a circuit on the engine and at the same time substitutes its own cur- 25 rent for the one which was broken. If such substitution takes place, *i. e.*, if the ramp is electrified the train may proceed, but if it is without current then the breaking of the circuit on the train prevents the train from 30 proceeding.

In the drawings I have shown the ramps as being located near the ends of abutting blocks. As a matter of fact, when a train reaches a ramp adjacent to one of the semaphores it will take enough current from the motor of the semaphore to bring the latter to danger position. If therefore the ramp be set out some distance from the end of the block, that is to say, toward the center 40 of the block the engineer on reaching the ramp will be able to proceed and the semaphore will first go to danger and then go to clear, so that the engineer is doubly assured of the condition of the track ahead. The 45 ramps are preferably placed in from the ends of the blocks, because if placed right at the signal, the engineer of the train would be right under the signal when it is released by the ramp, so that he could not see it go 50 to danger. My invention, however, contemplates placing the ramp at any suitable position between the center of the block and the end thereof.

From the foregoing description of the system it will be observed that when a train is in a section and a train from the opposite direction attempts to enter the section it will be stopped both by a signal at the end of the section which is operated no matter what block is occupied by the other train and also by the fact that the ramp at the end of the section has its current cut off. On the other hand, the arrangement is such that one train may follow another into the section, but it will be prevented from entering

the same block due to the fact that the first ramp immediately behind the first train is not electrified. This arrangement makes the device both absolute and permissive, that is to say, it is absolute as far as stopping op- 70 posing trains from entering the section is concerned, and it is permissive in that it permits trains which are proceeding in the same direction to enter the same section but prevents rear end collisions, because of the 75 fact that current is cut off from the ramps in the manner stated.

I claim:—

1. In a block signaling system, a pair of track rails, said rails being divided up into 80 a series of sections, each section being divided up into a plurality of blocks, the blocks of each section being insulated from one another, a ramp at each end of each block, all of said ramps being normally 85 electrified, and means for cutting off the current from the ramp at one end of the section when a train enters the opposite end of the section.

2. In a block signaling system, a pair of 90 track rails, said rails being divided up into a series of sections, each section being divided up into a plurality of blocks, the blocks of each section being insulated from one another, a ramp at each end of each 95 block, all of said ramps being normally electrified, means for cutting off the current from the ramp at one end of the section when a train enters the opposite end of the section, a signal at each end of the section 100 and means for displaying a danger signal near the ramp from which the current is cut off.

3. In a block signaling system, a pair of track rails, said rails being divided up into 105 a series of sections, each section being divided up into a plurality of blocks, the blocks of each section being insulated from one another, a ramp at each end of each block, all of said ramps being normally 110 electrified, and means for cutting off the current from a ramp of the block in the rear of the one in which the train is located.

4. In a block signaling system, a pair of track rails, said rails being divided up into 115 a series of sections, each section being divided up into a plurality of blocks, the blocks of each section being insulated from one another, a ramp in each block on one side of the track, a second ramp in each block on 120 the opposite side of the track and at the opposite end of the block, a relay at each end of each block for controlling the flow of current to the adjacent ramp in the adjacent block, each of the said relays being deener- 125 gized by the presence of a train in its particular block whereby the current is cut off from the ramp in the adjacent block.

5. In a block signaling system, a pair of track rails, said rails being divided up into 130

21

a series of sections, each section being divided up into a plurality of blocks, the blocks of each section being insulated from one another, a ramp in each block on one side of the track, a second ramp in each block on the opposite side of the track and at the opposite end of the block, a relay at each end of each block for controlling the flow of current to the adjacent ramp in the adjacent block, each of said relays being deenergized by the presence of a train in its particular block whereby the current is cut off from the ramp in the adjacent block, an auxiliary relay at each end of the section, a battery at each end of the section, the relay at one end of the section being energized by the battery at the other end of the section, each of said relays being controlled jointly by the relays at the ends of the blocks, the actuation of said last named relays depending upon the position of the train in the section.

6. In a block signaling system, a pair of track rails, said rails being divided up into a series of sections, each section being divided up into a plurality of blocks, the blocks of each section being insulated from one another, a ramp in each block on one side of the track, a second ramp in each block on the opposite side of the track and at the opposite end of the block, a relay at each end of each block for controlling the flow of current to the adjacent ramp in the adjacent block, each of said relays being deenergized by the presence of a train in its particular block whereby the current is cut off from the ramp in the adjacent block, an auxiliary relay at each end of the section, a battery at each end of the section, the relay at one end of the section being energized by the battery at the other end of the section, each of said relays being controlled jointly by the relays at the ends of the blocks, and a signal at each end of the section, said signals being controlled jointly by the said auxiliary relays and certain of the relays at the ends of the blocks, said signal having a normally closed circuit and the opening of the contacts of the auxiliary relays and one of the relays at the end of the block serving to break the circuit of the signal whereby the latter is moved to the danger position.

battery at the other end of the section, each 40 of said relays being controlled jointly by the relays at the ends of the blocks; and a signal at each end of the section, said signals being controlled jointly by the said auxiliary relays and certain of the relays at the 45 ends of the blocks.

7. In a block signaling system, a pair of track rails, said rails being divided up into a series of sections, each section being divided up into a plurality of blocks, the blocks 50 of each section being insulated from one another, a ramp in each block on one side of the track, a second ramp in each block on the opposite side of the track and at the 55 opposite end of the block, a relay at each end of each block for controlling the flow of current to the adjacent ramp in the adjacent block, each of said relays being deenergized by the presence of a train in its particular block whereby the current is cut 60 off from the ramp in the adjacent block, an auxiliary relay at each end of the section, a battery at each end of the section, the relay at one end of the section being energized by the battery at the other end of the 65 section, each of said relays being controlled jointly by the relays at the ends of the blocks, and a signal at each end of the section, said signals being controlled jointly by the said auxiliary relays and certain of 70 the relays at the ends of the blocks, said signal having a normally closed circuit and the opening of the contacts of the auxiliary relays and one of the relays at the end of the block serving to break the circuit of 75 the signal whereby the latter is moved to the danger position.

JUDSON SHOECRAFT.
